Inventor,

Chandler P. Simmons

United States Patent Office.

PHILANDER P. SIMMONS, OF DAVENPORT, IOWA.

Letters Patent No. 77,113, dated April 21, 1868.

IMPROVED BED-BOTTOM.

The Schedule referred to in these Letters Patent and making part of the same.

TO ALL WHOM IT MAY CONCERN:

Be it known that I, PHILANDER P. SIMMONS, of the city of Davenport, in the county of Scott, and State of Iowa, have invented certain new and useful Improvements in Bed-Bottom; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

I construct my improved bed-bottom in the following manner, to wit: A web of wooden slats is woven with small wire, which constitutes the surface for spreading the bedding upon. A frame is then made, of the desired size, to just drop or slide down inside of the bedstead proper, so as to rest upon the rails of bedstead in the place of common slats, which frame has the web, strained and straight, secured to it at each end by the wire of web being fastened on the upper edge of the frame by nails, and a strip of thin wood nailed on top of the same. On the under side of said frame are two cross-bars, at a certain distance from either end of frame, upon which are fastened spiral coiled springs, of four, six, or more on each bar, and each spring is fastened at the top to strips of wood running at right angles to said cross-bar.

Upon these latter strips of wood rests the web proper, which is fastened at each end of the top of frame, and any weight or body coming upon the upper surface of said web, causes it, to a certain extent, to conform to the shape of said body, thus making an agreeable, springy, and comfortable bed to lie upon. It is also very durable, and throws far less weight upon the springs, to keep it in proper position than in the common method.

In referring to the accompanying drawings—

Figure 1 is a plan of my invention,

Figure 2 is a longitudinal section, and

Figure 3 is a cross-section of the same.

Similar letters of reference refer to corresponding parts in the different figures.

a a are the side pieces or rails of the frame; *b b* are the ends of the frame; *c c* are the cross-bars at the bottom of the frame for springs to rest upon; *d d d* are the slats composing the web, and *e e e* are the strips of wood running along under, against, and at right angles to the slats of the web, and spring-bars at the bottom of frame, and which are fastened on top of springs, and act as a support to webs. *f f f* are the spiral springs, resting upon cross-bars *c c*, and fastened to and support bars or strips of wood *e e*. *g g g* are the wires that are woven into, and constitute, with slats *d d d*, the web and bed-bottom proper.

Having thus described my invention, what I claim is—

A spring-bed bottom, consisting of a web made of slats *d* woven together with wire, in combination with the wooden strips *e* and the spiral springs *f*, or their equivalents, when constructed and arranged substantially as described.

PHILANDER P. SIMMONS.
